(57) **CLAIM**

The ornamental design for a handle cap of fishing reel body, as shown and described.

DESCRIPTION

FIG. 1 is a perspective view of the top, front and left side of a handle cap of fishing reel body showing our new design; FIG. 2 is a perspective view of the bottom, rear and right side thereof;

FIG. 3 is a front elevational view thereof;

FIG. 4 is a rear elevational view thereof;

FIG. 5 is a top plan view thereof, the bottom view being a mirror image;

FIG. 6 is a right side elevational view thereof, the left side being a mirror image; and,

FIG. 7 is a perspective view thereof, while in use on the handle of a fishing reel body.

The portions shown in broken lines are for illustrative purposes only and form no part of the claimed design.
